EDWARD P. WHITNEY, OF STAMFORD, CONNECTICUT.

Letters Patent No. 77,427, dated April 28, 1868.

IMPROVEMENT IN INSTRUMENT FOR DRAWING NAILS.

The Schedule referred to in these Letters Patent and making part of the same:

TO ALL WHOM IT MAY CONCERN:

Be it known that I, EDWARD P. WHITNEY, of Stamford, in the county of Fairfield, and State of Connecticut, have invented a new and improved Instrument for Drawing Tacks, Nails, Spikes, &c.; and I do hereby declare that the following is a full, clear, and exact description of the same, reference being had to the accompanying drawing, forming part of this specification, in which—

Figure 1 is a side elevation of the instrument, the lower part thereof being shown in section.

Figure 2 is a plan or top view thereof.

Figure 3 is an inverted plan view of the shoe and claw part of the claw-head.

My invention consists in the combination, with a claw-head, of a foot or shoe, the former being pivoted, or so connected to the latter, that the requisite depression of the lever or handle, to draw the tack, can be effected without the heel of the claw-head resting upon the article into which the tack is driven, and hence the said article is not marred by the operation of drawing the tack.

A designates the claw-head, provided with a bifurcated forward end, *a*, as usual with tack-drawers, and *b* is the shank or lever for operating the said claw-head, provided, in the present instance, with a handle, *c*, (see fig. 1.) But the handle *c* may be dispensed with, and a tack-hammer connected to the end of the shank instead thereof, if desirable.

B is a foot or shoe, to which the claw-head is pivoted. In the present instance the pivot passes through the side-walls of the shoe, and through an eye in the claw-head, and holds the heel of the claw-head elevated in the shoe, the pivot being the fulcrum for the claw-head and shank. The bottom of the shoe has a smooth face, and its forward end has a piece removed, as shown in fig. 3, and the claw-head is so shaped that the face or lower side of the claw *a* projects through this opening, and when the claw is in its normal condition the said lower face of the claw *a* is flush with the bottom of the shoe, thus placing the claw in a proper position to push it under the head of the tack, as will appear obvious by reference to figs. 1 and 3.

C is a flat spring, having its upper end secured to the shank *b*, and its lower end curved, so as to bear upon the rear part of the shoe, the effect of which is to keep the lower face of the claw thrown down flush with the bottom or lower face of the shoe. I will here remark that other styles of springs can be applied to effect the same end; for example, a spiral spring could be set in, so that its respective ends would bear against the shoe and the heel of the claw-head. And I will further remark that it is not absolutely essential that any spring be employed, as the other parts would operate successfully without this feature.

I do not limit myself to the precise manner herein shown, of pivoting the claw-head in the shoe, nor to the exact construction herein shown. The object accomplished by my invention is to so combine the claw-head and shoe (with or without a spring) that in drawing tacks, the heel of the claw-head shall not bear upon the article into which the tack is driven, and thereby greatly lessen the liability of marring such article, which often occurs when tack-drawers of the ordinary construction are used.

I have found this instrument especially adapted to drawing the tacks in carriage-tops, where there is great danger of scratching or marring the leather or other article with which the frame is covered, if an ordinary tack-drawer be employed, whose heel bears on the article and mars it when the handle is depressed to draw the tack. With my invention, the flat face of the shoe rests firmly on the article, and is not moved during the drawing of the tack. The bifurcated end of the claw-head being flush on the under side with the bottom face of the shoe, enables the claw to be readily inserted under the head of the tack or nail.

What I claim as my invention, and desire to secure by Letters Patent, is—

1. The combination of the claw-head *A* and shoe *B*, constructed and operated substantially as and for the purpose herein specified.
2. A spring, *C*, in combination with the claw-head *A* and shoe *B*, substantially as and for the purpose specified.

EDWARD P. WHITNEY.
